UNITED STATES PATENT OFFICE.

WILLIAM GLADER, OF CHICAGO, AND HENRY SCHMIDT, OF ELGIN, ILLINOIS;
SAID GLADER ASSIGNOR TO SAID SCHMIDT.

TRUSSING-MACHINE.

SPECIFICATION forming part of Letters Patent No. 477,195, dated June 14, 1892.

Application filed June 4, 1891. Serial No. 395,042. (No model.)

To all whom it may concern:

Be it known that we, WILLIAM GLADER, a resident of Chicago, in the county of Cook, and HENRY SCHMIDT, a resident of Elgin, in the county of Kane, State of Illinois, citizens of the United States, have invented certain new and useful Improvements in Trussing-Machines, of which the following is a specification.

This invention relates to improvements in trussing-machines in which the truss-hoops are rigidly held and the staves forced through the truss-hoops in the final trussing operation preparatory to receiving the permanent hoops and otherwise finishing the article for the market, but more particularly relates to that class of trussing-machines especially adapted for trussing butter-tubs and other analogous articles, in which the staves are simultaneously driven through the truss-hoops and evened by the single stroke of a plate, weight, or other driver operating with continuous pressure upon the ends of the staves and forcing them downwardly through the truss-hoops against a fixed bottom, limiting the downward movement of the staves. In the trussing-machines now commonly employed, and particularly for trussing butter-tubs, the set-up tub after being fired is placed in a pot or between standards having shoulders or notches immovably supporting the truss-hoops, and the tub is trussed by repeated blows on the ends of the staves from a falling weight suspended over the pot or standards, the blows of which weight drive the staves downwardly through and tighten them in the truss-hoops, a fixed bottom in the pot or standards limiting the downward thrust of the staves. In the most approved construction of butter-tub trussing-machines now commonly used the truss-hoops are supported upon annular ledges or shoulders in a pot immovably arranged between vertical rods or standards, which serve as guides for the falling weight, said weight being lifted by means of a windlass and maintained in an elevated position by a clutch device until the clutch is actuated to release the weight, which then falls onto the ends of the staves, operating to drive the staves through the truss-hoops. Butter-tub trussing-machines of this general character—that is to say, in which the pot and standards are

fixed and a falling weight is used, whether or not a clutch mechanism is used in connection with that weight—are found in actual use to be objectionable, first, because in putting in and taking out the tub the operator must project his hands in the path of the falling weight, and the result is that he is frequently injured by a premature release of the weight, as often occurs in rapid operation of the machine; second, because the concussion of the blows of a falling weight and their necessary frequency subject the entire machine to a strain often resulting in breakage of its parts and necessitating frequent repairs, thereby incurring objectionable expense and loss of time; third, the concussions of the falling weight are not only objectionable, because of the noise they produce, but because of jarring and sometimes injuring the floor upon which the machine rests; fourth, because the hammer-like force of the blows of the falling weight frequently result in splitting or otherwise injuring the staves to such an extent that the tub must be knocked down, reset up, and again fired, when sound staves are substituted for the bad ones; fifth, because with a falling weight such tubs cannot be uniformly trussed, for with a falling weight neither the force of its blows or the number of its blows necessary to truss a tub can be regulated or predetermined, and, finally, because the use of a falling weight, requiring, as it does, a series of blows to truss a single tub, involves an objectionable loss of time and resultant expense in the trussing of butter-tubs. These are but few of the many objections to drop-weight trussing-machines, all of which a prolonged practical use of our invention demonstrates it to fully overcome and effectually provide against, as will now be more fully set forth.

Among the important objects of this invention is to automatically feed the article to be trussed into and discharge it from a trussing-machine, whereby the operation of the machine is quickened and possibility of danger to the attendant is wholly avoided, and the tubs so centered under the stave-driver that the pressure thereof is uniformly distributed to each and every stave and alike to every tub.

A further object is to thus uniformly drive

and even the staves by a single stroke of the driver, and in such a manner that there is an entire absence of any objectionable jarring of any part of the machine and liability of 5 injury thereto and to the staves themselves, while at the same time the staves during their downward movement through the truss-hoops have every freedom of movement necessary to enable them to conform themselves to each 10 other and to the truss-hoops.

Another object is to have the stroke of the driver uniform and also adjustable, whereby the staves in any given number of tubs may be uniformly trussed, and the strokes of the 15 driver may be changed to conform to staves varying in length—that is to say, to staves in tubs or other articles of differing heights.

Another object is to have a driver so constructed that all of the staves are uniformly 20 gathered—that is, moved inwardly to their final position in advance of their being driven home through the truss-hoops—whereby during the action of the drivers the staves have no lateral or frictional movement against the 25 face of the driver, and are therefore subject to no strain tending to mar their edges or splinter them.

Another object is to prevent any possibility 30 of the staves adhering to the gatherer and thereby being lifted by the driver as the latter is moved away from the staves after trussing them, and to accomplish this end by simple and effective means not liable to get out of order.

35 One of the more important objects of this invention is a trussing-machine in which the article to be trussed is automatically fed to or moved under the driver for trussing and away from the driver after being trussed— 40 that is to say, a machine in which the pot, standards, or other device receiving the set-up tub and supporting the truss-hoops is mechanically and automatically movable in and away from the path of travel of the driver— 45 whereby the attendant of the machine is entirely removed from danger by the action of driver, the article to be trussed is with certainty centered under said driver, the placing of the article and its removal from the pot 50 or standards are facilitated, and the operation of trussing substantially and materially quickened.

Another object is to have the pot or standard-supporting carriage transmitting the tub into and out of the machine of such a character that it is movable with the minimum amount of friction and yet capable of solidly sustaining the full impact of the driver without injury to or undue pressure upon the anti- 55 friction devices constituting the support of the carriage during its back-and-forth travel.

A still further object is to have such a connection between the stave-driver and the supporting-carriage that the time of their movement will be such that the article to be trussed is with certainty centered under the driver before any of the staves are subject to its ac-

tion and that no outward movement of the carriage shall take place until the driver has receded from contact with them, and, finally, 70 certain other objects to be attained, which are hereinafter described, claimed, and shown in the accompanying drawings, in which—

Figure 1 illustrates a side elevation of a trussing-machine embodying our invention 75 and showing the position of the several parts when the stave-driver is at the limit of its upward stroke and the automatic feed-carrier at the limit of its outer stroke with the pot, having therein a butter-tub in position to receive its final trussing; Fig. 2, a vertical central longitudinal section of the same, with the lever-and-link connection of the traveling carriage shown in elevation; Fig. 3, a detail sectional view of the stop device, limiting the inward movement of the feed-carrier; Fig. 4, an enlarged detail sectional view of the stave-driver, more particularly showing the form and arrangement of the gathering device secured thereto; Fig. 5, a detail longitudinal 90 section of the feed-carrier and its bed-plate on the line 5 5 of Fig. 7; Fig. 6, a vertical section through the pot on the line 6 6 of Fig. 7, more particularly showing the latch devices, preventing the driver lifting the trussed article during the retreat of the driver therefrom; Fig. 7, a top plan view of our machine with the driver and all that portion of the machine above the pot removed; Fig. 8, a detail side elevation on the line 8 8 of Fig. 7, 100 showing the latch connection between the throw-off lever and the crank-shaft connection with the movable carriage, whereby the carriage is automatically stopped at the limit of its backward stroke, and Fig. 9, a detail 105 elevation of the end of the rocking lever.

Similar letters and numerals of reference indicate the same parts in the several figures of the drawings.

The frame of our machine consists of a base 110 A, to each side of which are bolted or otherwise secured bifurcated standards B, the upper and stem ends of which B' are vertically slotted and connected by a cross-bar B², cast or otherwise secured thereto. Along the rear side of this frame-work is a power-shaft C, journaled in brackets C', bolted or otherwise secured to the standards B, on one end of which shaft is a belt-wheel C², made fixed or idle thereon by a clutch D, which may be of any ordinary construction, and therefore not shown in detail, the opposite end of said shaft having thereon a fixed pinion C³, meshing with a gear E on a shaft E', extending entirely across the machine, and having fixed 115 thereon next the gear E a pinion E², in turn meshing with a gear F, fixed upon a shaft F', which, like shaft E', (see Fig. 1,) is journaled in the base A and, as indicated by dotted lines in Fig. 7, extends entirely across said bed-plate and has upon its end a gear G, meshing with a pinion G' on the shaft E', as indicated in Fig. 7, whereby the power of said shaft E' is uniformly distributed as nearly as 120 125 130

may be to both ends f , the shaft F' , and the gears F and G thereon; but it would be no substantial departure from this invention to have the shaft E' a short shaft, omitting the 5 pinion G' , and with it the wheel-like structure of the gear G , for, as will now be shown, said gear G is in operation simply a crank-arm on the shaft F' ; or, in other words, gears F and G are each provided with crank-pins 10 F^2 , on which are pivoted crank-rods $H H'$, respectively, preferably made in two parts, connected by turnbuckles H^2 , one of which only is shown in Fig. 1, provided for increasing and decreasing the length of these crank-rods 15 for the purpose hereinafter described.

Crank-rods $H H'$ are respectively pivoted to boxes I , one of which is shown in Fig. 1, having a vertical sliding movement in the slotted upper frame-work B' , which said sliding boxes are secured to a cross-head I' , to which the driver J is attached, but may be secured to the driver, a rod I^2 , secured to this cross-head or to the driver, and bearing in the cross-bar B^2 , serving as an additional 20 guide to direct the driver; but the omission of the guide-rod I^2 would not be a substantial departure from our invention. By this rod connection of the driver with the crank-pin F^2 of the gear F the driver is operated, and the 25 range of its stroke may be changed by adjusting the turnbuckle H^2 , whereby the stroke of the driver may be varied for staves differing in length—that is to say, while the stroke of the driver always remains the same, by lengthening or shortening the rod H the range of 30 the action of the driver will be changed, and it will be brought nearer to or farther from the trussing-pot or bed of the machine at each stroke, according to the adjustment— 35 and by this turnbuckle the stroke of the driver may be so nicely adjusted that its downward stroke ceases as soon as the lower ends of the staves reach the bottom of the pot or bed-plate thereof, which they are caused to do by 40 a single stroke of the driver, and when so driven the final trussing of the tub is completed. In this connection it may be observed 45 that if the upper ends of the staves are not all even during the descent of the driver 50 thereon they will be with absolute certainty the moment the driver has completed its downward stroke.

The pot K , except certain slots hereinafter referred to, is of the usual form—that is to 55 say, is provided with shoulders $1 2 3$, in which the truss-hoops 1^a , 2^a , and 3^a of the butter-tub or other article to be trussed rest, and next its bottom with an annular flange 4 , constituting the bed or base plates thereof, upon 60 which the ends of the staves rest when fully driven into the truss-hoops; but if preferred said base 4 may be formed by a ring or plate set in the bottom or by a solid bottom in the pot. A butter-tub or other article to be trussed 65 is placed in this pot with the truss-hoops resting on the shoulders $1 2 3$, in which position the lower ends of the staves or some of them

are above the base of the pot, which during the operation of trussing is centered under the driver. As the staves are driven downwardly through the truss-hoops, all of them necessarily bodily and laterally move inwardly toward the axis of the tub, and this is true whether said staves are driven by a falling weight, by a hammer of any kind, or by the continuous single stroke of a driver actuated by crank-arms, as herein shown, or by cams. The effort of this inward movement of the staves is made during the contact of the driver with the stave ends, the result being in practice that not only are the stave ends sprung, splintered, and otherwise disfigured and injured to an extent frequently requiring new staves to be substituted for the injured ones, which involves a resetting up 80 of the tub, and if more than one stave is injured a refiring of the same, but a resistance to the action of the driver, only overcome by an increase in the force of its blow, promoting the frictional resistance and the tendency 85 of the staves to injury. By our invention, however, no such frictional resistance can occur, and the force of the driver is exerted throughout its stroke on a line directly through the staves from end to end, and the 90 staves are perfectly trussed by a blow, the force of which is so reduced that it cannot possibly injure the staves in the least. To these ends we employ a device termed for convenience a "gatherer," because it gathers the 95 staves to the limit of their inward movement before the driver can exert its full force to drive the staves downwardly through the truss-hoops. The gatherer consists of a ring 100 J' , bolted or otherwise secured to and projecting below the striking face of the driver, which, by the way, is preferably slightly concaved, so that its force is exerted on a line directly through the staves from end to end after they are gathered to the limit of their inward movement. Gatherer J' has its inner 105 face or edge J^2 flaring or bell-shaped from its upper or inner edge toward its lower or outer edge, as more clearly shown in Fig. 4, the diameter of the lower edge or perimeter of said 110 gatherer being as great or greater than that of the tub before it is trussed and its upper-edge diameter corresponding with the least outer diameter the staves can have when 115 finally trussed, so that immediately said gatherer comes in contact with the staves it gradually forces the staves inwardly until they reach the limit of their inward movement, until which time the face of the driver can have no contact with the staves. Now as the driver 120 descends the staves are first moved by the gatherer to the limit of their inward movement and the driver continuing its descent drives the staves home through the truss-hoops, and by these means not only is a lateral frictional movement of the staves against 125 the face of the driver entirely absent, but the staves are brought into the best possible position for utilizing the force of the driver, the 130

result being that a much less force is required to drive the staves home and the force necessary for that purpose so reduced that there is no possibility of battering or otherwise injuring the staves, while at the same time they are as completely and perfectly tightened as is possible by any number of blows from a falling weight or other form of driver. There is, however, a liability at times for the gathering-ring to so tightly embrace the staves as to cause the tub to be lifted from the pot as the driver ascends; but any such lifting tendency may be and is entirely prevented by the employment of very simple devices consisting of one, two, or more latches 5 5, (see Fig. 6,) pivoted at their lower ends toward or near the bottom of the pot and terminating at their upper ends in hooks, which when the pot and tub are under the hammer project through slots 7 7 in the upper edge of the pot and lap or hook over upon the upper truss-hoop, thereby holding the tub down in the pot as the driver ascends. These latches are actuated to make their inward movement by means of fixed spring-arms 8 8 as the carriage herein-after described, moves to carry the pot and tub under the driver, but which are caused to recede from the truss-hoop and release it by means of springs 9 9, (see Fig. 6,) confined 30 between the latches and the pot and in staples 10 10, which serve to limit the outward movement of the latches, it being understood that when the tub is at the limit of its outward stroke the latches are disengaged from the spring-arms 8 8, when they are actuated by their springs 9 9 to release the truss-hoops. Our invention, however, is not limited to the special form or means of actuating such latches, but broadly includes any form of 40 latch actuated by hand or automatically to hold the tub down in the pot as the driver ascends after completing its stroke, for, so far as we know, devices of any kind for this purpose are wholly new.

45 As before stated, there is a serious objection to trussing-machines as now employed, because of the danger to the attendant in the putting into and taking the tubs from the machine, for that in the machines now commonly used the attendant both in putting the tubs into the machine and taking them out must put his hands into the pathway of the driver in taking hold of the upper edge of the tub to lift it out of the pot, the result being that not infrequently the driver will injure the attendant either by an accidental fall or in the course of a rapid operation of the machine, and several instances of this character have resulted in crushing the hand 55 and fingers of the attendant.

60 One of the most important features of a trussing-machine embodying our invention is the entire absence of any possibility of injury to the attendant by the driver, and by reason of our invention automatically feeding the tub under the driver and entirely removing it from the path traveled by the

driver immediately the tub is trussed ready for removal. To accomplish this novel and important result, the pot K is mounted upon and secured to a carriage L, which may be supported upon the base A of the machine, but is preferably so supported upon a bed-plate M. In order that this carriage may freely move upon the bed-plate, it is mounted upon anti-friction rollers 11 11 (see Fig. 5) and in a peculiar and novel manner, for, obviously, no rollers pivoted directly to the carriage could have their pivots withstand the force of the driver, and if they could the carriage would not be sufficiently solid for thoroughly practical purposes. In order, therefore, to entirely relieve the rollers from the force of the driver and to enable a carriage to rest flat and solidly upon the bed-plate, the rollers have their 80 bearings in suitable blocks 12, suspended from the free ends of the spring-bar 13, supported by and above the plane of the table by adjustable bolts 14, screwed into the carriage through slots 15, in which carriage the rollers 90 project so as to rest upon the bed-plate of the carriage. These spring-bars 13 are of sufficient tension and stiffness to resist the combined weight of the carriage, the pot, and the tub, so as to lift the carriage above the bed-plate and to permit the rollers to support the carriage thereon, which they do at all times, except during the descent of the driver upon the staves, and therefore permit the carriage to freely move back and forth over the bed-plate with the least possible amount of friction. With the carriage under the driver the force of the driver on the ends of the staves overcomes the resistance of the spring-bars 13 and as a result forces the carriage flat upon 105 its bed-plate; but the moment the pressure of the driver is removed the table is lifted free from the bed-plate by the spring-bars and entirely supported upon its anti-friction rollers. Should the spring-bar be bent after frequent 110 operation so as to lose its power to lift the carriage, this loss of power may be compensated for by lowering the screw-bolts 14 and with them the spring-bar, the bolts being locked in whatever position they may be adjusted by means of the lock-nuts 16. (Clearly shown in Fig. 5.)

To cause the back-and-forth movement of the carriage L, it is provided at its rearward end with a lug 17, connected by a link 18 with 120 a rocking lever 19, fulcrumed on a pivot 20 in the frame of the machine, as shown in Fig. 2, the upper and short arm of which lever terminates in a T, as shown in Fig. 9, the free ends 21 of which T project into a two-part 125 angular camway 22, formed in the inner face-plates 23, between which plates the lever 19 projects. The camway-plates 23 are cast or otherwise secured to the face-plate 24, in turn adjustably secured to the block I' of the 130 driver by bolts 25, (see Fig. 1,) projected through elongated slots 26 and screwed into the block I', the face-plate 24, and the camway, being vertically adjustable and locked

in that adjustment by bolts 27, the upper one of which has its head resting upon the block I', with its screw-threaded end working in a lug projecting from the face-plate 24, the lower screw-bolt 27 working in a corresponding lug in the face-plate 24, with its end abutting against the under side of the block I', as shown.

To vertically adjust the camway, the bolts 25 are first loosened, and after turning the bolts 27 to get the desired adjustment the bolts 25 are then tightened, thereby operating, in conjunction with the bolts 27, to lock the camway in whatever adjustment it may be given. This adjustment of the camway is important in that it provides for timing the movements of the tub according to the stroke of the driver, when the latter is changed to adapt it for trussing tubs of different heights, for under all conditions the tub must come to a center beneath the driver before the latter engages the staves and must remain in that position until the trussing operation is completed and the driver disengaged from the staves, and obviously in trussing tubs of differing heights the range of action of the driver must be changed according to the height of the tub, and the position of the cam must be correspondingly changed in order to produce the desired result.

In operation when the driver is at the limit of its upward stroke, as illustrated in Fig. 1, the end of the rocking lever 19 is near the lower end of the camway 22, and the carriage 35 is at the limit of its backward or outer movement in position to receive or to have removed therefrom a tub. As the driver descends to perform the trussing operation, the camway descends with it, and in so doing the 40 oblique portion of the camway actuates the rocking lever so as to swing it to its opposite extreme position illustrated in Fig. 2, drawing the carriage forward into the machine, and centering the tub under the driver, the forward movement of the carriage and tub ceasing 45 immediately the T end of the lever enters the vertical portion of the camway, and it is not until the tub is so centered that the gatherer of the driver is in contact with the staves 50 of the tub. The further descent of the driver and camway in completing the trussing operation has no effect upon the tub, which remains at rest during such movement because of the working of the T on the lever in the 55 vertical portion of the camway; and it will thus be seen that the tub will remain at rest during the entire trussing operation, and that it is not until after the driver has cleared the staves on its return or upward movement that 60 the inclined portion of the camway causes the rocking lever 19 to again swing on its fulcrum and move the carriage with the pot and trussed tub out from under the driver back to the position shown in Fig. 1 for the removal of the tub and the insertion of a new one 65 to be trussed. It will therefore be understood that while the stroke of the driver and the cam-

way is always the same the range of its action varies materially, according to the height of the tub to be trussed, the position or range 70 of action of the driver and camway being readily changed by means of the turnbuckles in the crank-rods II, and the position of the camway with relation to the driver must be changed accordingly, so that the carriage may be moved 75 in time with the driver, being lowered when the driver is raised for the trussing of the higher tubs, and raised when the carriage is lowered for the trussing of the lower or shorter tubs. The lever 19 is also shown as provided 80 with laterally-adjustable bearings; but this feature is simply for convenience in putting the parts together, and has no other duty to perform after the parts are once adjusted and secured in place.

The connections between the movable carriage, as shown, while of the preferred form and found successful in practical operation, may be of other forms and arrangements, without departing from the spirit of our invention, which includes, broadly, any connection between the carriage and the driver or any other portion of the machine by which the table may have the movements described, and also in a more limited sense, by which 95 the action of the driver causes the table to move in proper time therewith to center and truss the tub and discharge it from the machine, as has been described.

In the practical operation of the machine a 100 slight interval is required in which to remove the trussed tub from the pot and insert a new one, and in order to save time and avoid the danger of breakage of any of the parts of the machine, a result of the carelessness of the 105 operator, we have preferred to make a stoppage of the machine after each trussing operation automatic by some suitable means—such as the ordinary hand-lever D'—pivoted at D² to a suitable projection or fixed portion of the machine, and having at its forward end a yoke D³, engaging and operating the clutch D, while the opposite or free end of the lever works through and is guided in a slotted bracket or projection D⁴. This lever 110 is normally actuated to throw the clutch out of engagement by a coil-spring a on the rod b, pivotally connected to the lever D', near the other end thereof, and working in a socket-piece c, between which socket-piece and a 115 shoulder or collar d on the rod the spring is confined.

Near the free end of the hand-lever D' is rigidly secured one end of a stop-bar e, provided with an inclined lug e', adapted and 120 arranged to be engaged by a crank-arm f on the rocking shaft f', journaled in suitable bearings secured to the frame of the machine, to the opposite inner end of which shaft (see Figs. 2, 7, and 8) is secured another crank-arm 125 f², which for clearness is designated as a stop-arm and which projects downwardly into the path of a laterally-projecting lug or shoulder f⁴ on the carriage L. The rocking shaft f' is

actuated in one direction by means of a coil spring f^3 , secured at its ends, respectively, to the free end of the stop-arm and the frame of the machine, so as to cause the crank-arm

- 5 f on the opposite end of the shaft to normally bear against and engage the lug or stop upon the stop-bar e ; but when the carriage is moved to the limit of its backward stroke—that is, to the position shown in Fig. 7—the 10 lug or shoulder f^4 thereon strikes against the stop-arm f^2 , so as to overcome the tension of the spring f , rock the shaft f' in the opposite direction, and free the arm f from the lug on the stop-bar, which latter device operates as 15 a latch.

With the parts in the position shown in Fig. 7, to start the machine the operator pulls the hand-lever inwardly against the tension of the spring a , thus throwing the clutch D 20 into engagement, and starts the machine into operation, holding the lever for an instant in this position until the carriage slides forward sufficiently to let the spring f^3 operate the rock-shaft, and cause the engagement of the 25 crank-arm f with the latch e , when the clutch will be carried into engagement. The parts will remain in this position until the carriage has moved forward, the trussing operation 30 has been completed, and the carriage returned to its first position, just before reaching which the lug f^4 thereon strikes the stop-arm f^2 on the rock-shaft, and causes the 35 disengagement of the crank-arm f with the latch, when the spring a will throw the lever outward, and thus disengage the clutch and instantly arrest the operation of the machine.

While answering every purpose in practice, we do not desire to limit ourselves to 40 this form of connection between the throw-off lever D' and the carriage; but it would be no departure from the spirit of our invention to use any other form of stop connection answering the same purpose, many of which are 45 well-known to those skilled in the arts.

In order to relieve the various parts of the machine from strain, we have also provided stop devices for limiting the inward or forward movement of the carriage, which stop 50 devices, as illustrated in the drawings, practically consist of a piston or plunger device confining a yielding packing, such as that illustrated in Fig. 3, consisting of the socketed brackets g , secured to the bed-plate M at 55 each side of the machine, in the socket of each of which is secured a rubber ring or gasket g' , through which passes the stem of a piston g^2 , into which is screwed an adjustable stop-bolt g^3 , which is locked in its adjustment 60 by a nut g^4 , which provides for taking up the wear of the yielding packing and of the other parts of the machine and also serves to cushion the carriage when it strikes against the seat. The stem of the piston g^2 may be held against 65 withdrawal from the bracket by any suitable means, as by the collar and set-screw shown in Fig. 3.

While our machine has been described and illustrated in its use upon butter-tubs, it is obvious that it is equally applicable to machines for trussing barrels, kegs, and other devices, for obviously no change in the machine is required for such purposes other than dimensions and form of pot best adapted for the particular article to be trussed; and, furthermore, we do not recognize that there is any substantial distinction in the character of the operation required for trussing butter-tubs as compared with trussing barrels, kegs, and bucket-like structures.

Having described our invention, what we claim, and desire to secure by Letters Patent, is—

1. In a trussing-machine, the combination, with a reciprocating driver and a movable 85 trussing-pot having annular ledges for the hoops or trussing-rings and a rest or stop at its bottom for the staves, of mechanism for automatically operating said driver and pot, so as to cause the pot to move to a center under the driver, remain at rest during the trussing operation, and move out from under the driver after the trussing operation, substantially as and for the purpose described.

2. In a trussing-machine, the combination, 95 with a reciprocating driver, means for adjusting the range of reciprocation of said driver, and a movable trussing-pot having ledges for the trussing rings or hoops and a rest or stop at its bottom for the staves, of mechanism for automatically operating said driver and pot, so as to cause the pot to move to a center under the driver, remain at rest during the trussing operation, and move out from under the driver after the trussing operation, substantially as and for the purpose described.

3. In a trussing-machine, the combination, with a vertically-reciprocating driver and a horizontally intermittent reciprocating trussing-pot having horizontal annular ledges for the trussing rings or hoops, and a rest or stop at its bottom for the staves, of mechanism for automatically operating said driver and pot, so as to cause said pot to move to a center under the driver, remain at rest during the trussing operation, and move out from under the driver, substantially as and for the purpose described.

4. In a trussing-machine, the combination, with a vertically-reciprocating driver, means 120 for adjusting the range of reciprocation of said driver, and a horizontally-intermittent reciprocating trussing-pot, having annular ledges for the trussing-hoops and a rest or stop at its bottom for the staves, of mechanism for automatically operating said driver and pot, so as to cause said pot to move to a center under the driver, remain at rest during the trussing operation, and move out from under the driver, substantially as and for the 125 purpose described.

5. In a trussing-machine, the combination, with a reciprocating driver and a movable trussing-pot having longitudinal ledges for the

hoops and a rest or stop at its bottom for the staves, of a connection between said driver and pot, whereby the pot will be moved to a center under the driver, remain in that position during the trussing operation, and move out from under the driver simultaneously with and during the reciprocation of the driver, substantially as and for the purpose described.

10 6. In a trussing-machine, the combination, with a reciprocating driver, means for adjusting the range of reciprocation of said driver, and a movable trussing-pot having annular ledges for the hoops and a rest or stop at its bottom for the staves, of a connection between said driver and pot, whereby the pot will be moved to a center under the driver, remain in that position during the trussing operation, and move out from under the driver simultaneously with and during the reciprocation of the driver, substantially as and for the purpose described.

15 7. In a trussing-machine, the combination, with a reciprocating driver and a movable trussing-pot having annular ledges for the hoops and a rest or stop at its bottom for the staves, of a cam and lever connection between said driver and pot, whereby the latter will be moved to a center under the driver, remain at rest during the trussing operation, and move out from under the driver during the reciprocation of the driver, substantially as described.

20 8. In a trussing-machine, the combination, with a reciprocating driver, means for adjusting the range of reciprocation of said driver, and a movable trussing-pot having horizontal ledges or shoulders for the hoops and a rest or stop at its bottom for the staves, of a cam and lever between said driver and pot, whereby the latter will be moved to a center under the driver, remain at rest during the trussing operation, and move out from under the driver during the reciprocation of the driver, substantially as described.

25 9. In a trussing-machine, the combination, with a reciprocating driver and a movable trussing-pot having horizontal ledges or shoulders for the hoops and a rest or stop at its bottom for the staves, of a cam attached to and movable with the driver and a lever connected at one end with the pot and at the opposite end with the cam, so as to be actuated thereby during the reciprocation of the driver, substantially as and for the purpose described.

30 10. In a trussing-machine, the combination, with a reciprocating driver, means for adjusting the range of reciprocation of said driver, and a movable trussing-pot having hoop-supporting ledges or shoulders and a support at its lower end for the staves, of a cam attached to and movable with the driver and a lever connected at one end with the pot and at the opposite end with the cam, so as to be actuated thereby during the reciprocation of the driver, substantially as and for the purpose described.

11. In a trussing-machine, the combination, with a reciprocating driver and a movable trussing-pot having hoop-supporting ledges or shoulders and a rest or stop at its lower end for the staves, of a cam secured to and movable with the driver and a lever connected at one end with the pot and at its opposite end engaging and operated by said cam, substantially as described.

15 12. In a trussing-machine, the combination, with a reciprocating driver, means for adjusting the range of reciprocation of said driver, and a movable trussing-pot having supporting ledges or shoulders and a rest or stop at its lower end for the staves, of a cam secured to and movable with the driver and a lever connected at one end with the pot and at its opposite end engaging and operated by said cam, substantially as described.

20 13. In a trussing-machine, the combination, with a reciprocating driver, means for adjusting the range of reciprocation of the driver, a trussing-pot, and a movable carriage supporting and carrying said pot, of a cam adjustably secured to the driver and a lever, one end of which engages and is operated by said cam, and a link connection between the opposite end of said lever and the carriage, substantially as described.

25 14. In a trussing-machine, the combination, with a reciprocating driver, crank-wheels, crank-rods connecting said wheels and driver, turnbuckles in said rods for adjusting the length thereof, and a movable trussing-pot, of a cam adjustably secured to the driver, and a lever connected at one end with said pot and at its opposite end engaging and actuated by said cam, substantially as described.

30 15. In a trussing-machine, the combination, with a reciprocating driver adapted to engage the ends of the staves and a gatherer attached thereto for gathering the ends of the staves before their being operated upon by the driver, of a movable trussing-pot having truss hoop or ring supporting ledges or shoulders and mechanism for operating said driver and pot, substantially as described.

35 16. In a trussing-machine, the combination, with a reciprocating driver having a concaved operating-face and a gathering-ring attached thereto, the operating-face of which curves or inclines inwardly to the face of the driver, of a movable trussing-pot and mechanism for operating said pot and driver, substantially as described.

40 17. In a trussing-machine, the combination, with a reciprocating driver adapted to engage the ends of the staves and a movable trussing-pot having hoop-supporting ledges or shoulders, of mechanism for automatically operating said driver and pot, so as to cause the latter to move to a center under the driver, remain at rest during the trussing operation, and move out from under the driver after such operation, and a gatherer attached to the driver for gathering the upper ends of the staves to their normal position before being

operated on by the driver, substantially as described.

18. In a trussing-machine, the combination, with a vertical reciprocating driver and a horizontally-intermittent reciprocating trussing-pot and mechanism for automatically operating said driver and pot, so as to cause the latter to move to a center under the driver, remain at rest during the trussing operation, and move out from under the driver after such operation, of a power-shaft and clutch thereon and a stop device connecting said clutch and pot, so as to automatically throw the clutch out of engagement after each complete operation of the machine, substantially as described.

19. In a trussing-machine, the combination, with a vertically-reciprocating driver, a horizontally-intermittent reciprocating trussing-pot, and mechanism for simultaneously operating said driver and pot, so as to cause the latter to move to a center under the driver, remain at rest during the trussing operation, and move out from under the driver when such operation is completed, of a power-shaft, clutch thereon, a spring-actuated hand-lever normally throwing such clutch out of engagement, a lock device engaging said lever, so as to lock the clutch into engagement, and means whereby said lock device is released by the pot on its outward movement from under the driver, substantially as described.

20. In a trussing-machine, the combination, with a vertically-reciprocating driver, a horizontally-intermittent reciprocating trussing-pot, and mechanism for simultaneously operating said driver and pot, so as to cause the latter to move to a center under the driver, remain at rest during the trussing operation, 35 and move out from under the driver when such operation is completed, of the power-shaft, clutch thereon, a spring-actuated hand-lever normally throwing such clutch out of engagement, a spring-actuated lock device 40 engaging said lever, so as to lock the clutch into engagement, and means whereby said lock device is released by the pot on its outward movement from under the driver, substantially as described. 45

50 21. In a trussing-machine, the combination, with a vertically-reciprocating driver, a horizontally-intermittent reciprocating trussing-pot, and mechanism for simultaneously operating said driver and pot, so as to cause the latter to move to a center under the driver, remain at rest during the trussing operation, and move out from under the driver when such operation is completed, of a power-shaft, clutch thereon, and spring-actuated hand-lever normally throwing said clutch out of engagement, a latch on said lever, a spring-actuated rock-shaft, a crank-arm thereon engaging said latch, and a stop-arm thereon engaged and operated by the pot, so as to disengage the crank-arm from the latch, substantially as described.

22. In a trussing-machine, the combination, with a reciprocating driver, of a movable trussing-pot provided with annular shoulders for supporting the trussing-rings, and mechanism for automatically operating said driver and pot, so as to cause the latter to move to a center under the driver, remain at rest during the trussing operation, and move out from under the driver when such operation is completed, latches attached to the pot, and means for automatically operating said latches to engage the upper truss-ring when the pot moves to a center under the driver and disengaged from the same when the pot moves out from under the driver, substantially as described. 70 75 80

23. In a trussing-machine, the combination, with a reciprocating driver, of a movable trussing-pot provided with annular shoulders for supporting the trussing-rings, and mechanism for automatically driving said driver and pot, so as to cause the latter to move to a center under the driver, remain at rest during the trussing operation, and move out from under the driver when such operation is completed, spring-actuated latches attached to the pot, and means for automatically operating said latches to engage the upper truss-ring when the pot moves to a center under the driver and disengaged from the same when the pot moves out from under the driver, substantially as described. 85 90 95

24. In a trussing-machine, the combination, with a reciprocating driver, a gatherer attached thereto for gathering the staves to their normal position prior to being operated upon by the driver, and a movable trussing-pot provided with annular shoulders for supporting the trussing-rings, of mechanism for automatically operating said driver and pot, so as to cause the latter to move to a center under the driver, remain at rest during the trussing operation, and move out from under the driver when such operation is completed and the gatherer disengaged from the staves, latches, and means for automatically operating said latches to engage the upper truss-ring when the pot moves to a center under the driver and disengaged therefrom when the pot moves out from under the driver, substantially as described. 115

25. In a trussing-machine, the combination, with a reciprocating driver, a gatherer attached thereto for gathering the staves to their normal position prior to being operated upon by the driver, and a movable trussing-pot provided with annular shoulders for supporting the trussing-rings, of mechanism for automatically operating said driver and pot, so as to cause the latter to move to a center under the driver, remain at rest during the trussing operation, and move out from under the driver when such operation is completed and the gatherer disengaged from the staves, spring-actuated latches, and means for automatically operating said latches to engage the upper truss-ring when the pot moves to

a center under the driver and disengaged therefrom when the pot moves out from under the driver, substantially as described.

26. In a trussing-machine, the combination, with a reciprocating driver and gatherer attached thereto for gathering the ends of the staves prior to their engagement by the driver, and a movable trussing-pot provided with annular shoulders for supporting the trussing-rings, of mechanism for automatically operating said driver and pot, so as to cause the latter to move to a center under the driver, remain at rest during the trussing operation, and move out from under the driver after such operation is completed, of spring-actuated latches pivoted to and movable with the pot for engaging the upper truss-rings and means for overcoming the tension of said springs and forcing the latches into engagement with the upper truss-ring when the pot moves to a center under the driver, substantially as described.

27. In a trussing-machine, the combination, with a reciprocating driver, a gatherer secured thereto for gathering the ends of the staves prior to being operated upon by the driver, and a trussing-pot provided with annular shoulders for supporting the trussing-rings, of mechanism for automatically operating said driver and pot, so as to cause the latter to move to a center under the driver, remain at rest during the trussing operation, and move out from under the driver when such operation is completed, latches for engaging the upper truss-ring, springs normally holding said latches out of engagement with said ring, and springs forcing the latches into engagement with the truss-rings when the tub is moved to a center beneath the driver, substantially as described.

28. In a trussing-machine, the combination, with a reciprocating driver and an intermittently - reciprocating trussing - pot having hoop-supporting ledges or shoulders and a rest or stop at its lower end for the staves, of mechanism for automatically operating said driver and pot, so as to cause the latter to move to a center under the driver, remain at rest during the trussing operation, and move out from under the driver after such operation, and a cushioned stop device for limiting the movement of the pot, substantially as described.

29. In a trussing-machine, the combination, with a reciprocating driver and an intermittently-reciprocating trussing-pot, of mechanism for automatically operating said driver and pot, so as to cause the latter to move to a center under the driver, remain at rest during the trussing operation, and move out from under the driver after such operation, and a stop device for limiting the inward movement of the pot, comprising a socketed bracket and piston working therein, a yielding cushion between said piston and bracket and the end of the socket in the bracket, and an adjustable

stop-bolt projecting from said piston, substantially as described.

30. In a trussing-machine, the combination, with a reciprocating driver and movable trussing-pot and mechanism for automatically operating said driver and pot, so as to cause the latter to move to a center under the driver, remain at rest during the trussing operation, and move out from under the driver after such operation is completed, of a carriage supporting the trussing-pot, anti-friction rollers therefor, and a spring connection between said rollers and carriage, substantially as described.

31. In a trussing-machine, the combination, with a reciprocating driver and movable trussing-pot and mechanism for automatically operating said driver and pot, so as to cause the latter to move to a center under the driver, remain at rest during the trussing operation, and move out from under the driver after such operation is completed, of a carriage supporting the trussing-pot, having slots near the front and rear ends thereof, anti-friction rollers working in said slots and bearing upon the bed of the machine, a spring-bar extending between the bearings of said rollers, and a connection between the carriage and said bar between the rollers, whereby the carriage is yieldingly suspended from said bar, substantially as described.

32. In a trussing-machine, the combination, with the reciprocating driver, a trussing-pot and a movable carriage supporting and carrying said pot, of a cam adjustably secured to the driver, a lever engaged and operated by said cam at one end, a link connecting the other end of said lever with said carriage, and means for adjusting the range of reciprocation of said driver, substantially as set forth.

33. In a trussing-machine, the combination, with a vertically-reciprocating driver, a horizontally - reciprocating trussing-pot having hoop-supporting ledges or shoulders and a rest or stop at its lower end for the staves, and means for intermittently projecting said pot under the driver and withdrawing it therefrom, of automatic stop mechanism operated by the movement of the pot for rendering the latter inactive when in its withdrawn position, substantially as set forth.

34. In a trussing-machine, the combination, with the vertically-reciprocating driver and the trussing-pot having hoop - supporting ledges or shoulders and a rest or stop at its lower end for the staves, of the horizontally-reciprocating carriage supporting said pot and means for causing said carriage to intermittently move to center under the driver and to move outward again at the completion of the trussing operation, substantially as set forth.

35. In a trussing-machine, the combination, with the reciprocating driver adapted to engage the ends of the staves and an intermittently - reciprocating trussing - pot having

hoop-supporting ledges or shoulders and a rest or stop at its lower end for the staves, of a rigid gatherer secured to the driver and adapted to engage the staves in advance of said driver, substantially as set forth.

36. In a trussing-machine, the combination, with the reciprocating driver adapted to engage the ends of the staves and the intermittently reciprocating trussing-pot having

hoop-supporting ledges or shoulders and a

rest or stop at its lower end for the staves, of a rigid interiorly beveled or rounded gathering-ring adapted to engage the ends of the staves in advance of the driver, substantially as set forth.
